BAG SUPPORTING DEVICE

Lewis B. Eaton, Quincy, Mass., assignor to Pneumatic Scale Corporation, Limited, Quincy, Mass., a corporation of Massachusetts

Application May 16, 1941, Serial No. 393,767

10 Claims. (Cl. 226—51)

This invention relates to a bag supporting device for tea bagging machines.

The invention has for an object to provide a novel and superior construction of a bag supporting device for use in tea bagging machines of the type forming the subject matter of the United States patents to Williams, No. 2,071,244, granted February 16, 1937, and No. 2,351,382, granted June 13, 1944, and which is particularly adapted to more securely hold the bag in a closed position during the formation thereof, whereby to prevent slippage of the bag in its supporting device and also to prevent the escape of tea therefrom during its movement to the various mechanisms for producing the bag.

With this general object in view and such others as may hereinafter appear, the invention consists in the bag supporting device for tea bagging machines and also in the various structures, arrangements and combinations of parts hereinafter described and particularly defined in the claims at the end of this specification.

In the drawings illustrating the preferred form of the invention, Fig. 1 is a view in side elevation of a bag supporting device embodying the present invention; Fig. 2 is a view in front elevation of the bag supporting device shown in Fig. 1; Fig. 3 is a cross-sectional view of the bag supporting member shown in its closed position; Fig. 4 is a perspective view showing the bag supporting member in its open position; Fig. 5 is a plan view in cross section taken on the line 5—5 of Fig. 3; Fig. 6 is a view in side elevation illustrating the supporting device in a different position of operation and Fig. 7 is a plan view of a tea bagging machine showing the present bag supporting members carried by and mounted for pivotal movement on an endless chain.

In general, the present invention contemplates the provision of a bag supporting member or gripper of novel and improved construction particularly adapted to be mounted upon an endless carrier chain forming part of a tea bagging machine of the type illustrated and described in the United States patent to Williams, No. 2,071,244, issued February 16, 1937, or No. 2,351,382 granted June 13, 1944, and in such a machine provision is made for forming, filling and closing a tea bag of the so-called pillow or envelope type while the bag is held between the clamping jaws of a bag supporting member.

In the operation of such a tea bagging machine and as described in said Williams patents, the clamping jaws are arranged to be opened to

receive a folded web of bag forming material and as the supporting member is advanced, a filling tube is caused to enter between the sides of the folded web whereupon the clamping jaws are closed upon the web and the tube. Thereupon, a bag section held between the clamping jaws is severed from the web, and the bag section is provided with a charge of tea through the filling tube. The filling tube is then withdrawn and the supporting members are advanced past stitching mechanism where the open mouth and side edges of the bag are sewn to form the filled and closed bag.

As illustrated and described in the Williams patents above referred to, provision is made for mounting each bag supporting member to be capable of movement in a vertical plane whereby the bag may be moved from a vertical to a horizontal position and to be returned, and provision is also made for rotating the clamping jaws while disposed in their horizontal position whereby to successively present the open mouth and side edges of the bag to the various sewing mechanisms as the supporting members are continuously moved through the machine.

The tea bagging machines of the Williams type were particularly designed for the production of tea bags from cloth, such as fine mesh gauze, or other relatively yieldable material. The bag supporting members or grippers of the type heretofore employed have been satisfactory for supporting such cloth containers for the reason that the material being of a yieldable character, offered less resistance to the grippers and was thus more readily retained therebetween. Also, escape of the tea through the mouth and side edges of the bag was less likely to occur during the above-described movement through the machine because the edges of the bag making material tended to adhere together and also because the tea tended to cling to the fibers of the cloth thus being retained within the bag. However, when paper such as the usual filter paper or perforated parchment paper was substituted for cloth as the bag making material, the relatively firm and non-yielding character of the paper and also the relatively smooth surface thereof rendered it difficult to retain the bag in such prior grippers without slippage of the bag in its gripper as it passed through the various mechanisms of the machine, and it was also found that during the rotation of the bag as above described, the tea would become displaced and escape through openings in the mouth and side edges of the bag due to the inability of such prior grippers to success-

fully hold the paper containers in positively closed condition during such movement.

In accordance with one feature thereof the present invention aims to provide a construction of bag supporting member which is adapted to retain such paper containers in a tightly and positively closed condition during their movement through the machine so as to prevent slippage of the bag in the gripper during the various operations performed on the bag and so as to prevent escape of the tea therefrom. Although the present bag supporting members are particularly adapted for use with such paper containers, it is not desired to limit the invention in this respect since the present grippers may be embodied in a machine for producing tea bags from other materials as well.

In the grippers illustrated in the patent to Williams, above referred to, the clamping members were provided with an opening adjacent the mouth portion of the bag to enable the clamping members to be closed over the filling tube. Thus, when the filling tube was withdrawn the mouth of the bag was left in a substantially open condition so that during subsequent movement of the supporting member and the bag, as above described, the tea within the bag section was free to escape through such opening.

In accordance with another feature of the present invention, the clamping members are of a construction such as to permit them to be closed over the web of bag forming material and over the filling tube and to thereafter positively close the mouth of the bag after the filling tube has been withdrawn whereby to prevent escape of the tea from within the bag when the latter is moved from a vertical to a horizontal position and also to enable the clamping members to hold the mouth of the bag in a tightly closed position during the subsequent sewing operations.

Referring now to the drawings which illustrate the preferred embodiment of the invention, the present bag supporting member includes grippers 4 comprising a pair of clamping jaws 10, 12 arranged to be opened to receive a folded web of bag forming material 14, as shown in Figs. 1 and 2, and to be closed over a bag section as illustrated in Fig. 3. The clamping jaws are pivotally and yieldingly retained in a holder 16 in a manner such as to enable them to be yieldingly snapped into open or closed position. As herein shown, the side walls 18, 20 of the clamping jaws comprise flat springs arranged to pivot upon opposed open bearings 22, 24 provided in the holder 16. The bearings 22, 24 are rounded to receive the hooked ends 26, 28 of the side wall spring members 18, 20, as best shown in Fig. 3. The clamping jaws are also pivotally connected together upon a common center comprising a pin 30 arranged to be engaged by open bearings provided in the sides of the clamping jaws.

It will be observed that the pin 30 is movable relative to the spring wall pivots 22, 24 so that in operation, when pressure is applied to the pin 30 in one direction, the pin is yieldingly moved to open the jaws, and when the pin is moved beyond the dead center line through the pivots 22, 24, the jaws will be snapped into their open position. The clamping jaws are limited in their opening movement by the engagement of the cut away portions 32, 34 provided in the jaws below the pin 30, as clearly shown in Figs. 1 and 3. As illustrated in Fig. 3, an opening 35 is provided in the holder 16 for the reception of a pressure ap-

plying member 21 as diagrammatically illustrated in Fig. 7, arranged to be projected against the pin 30 during the operation of the machine. In practice, the jaws are preferably urged into their closed position against the pressure of the spring walls 18, 20 by the application of pressure against either one or both sides of the jaws, such as by a rubber covered roller 44, shown in Fig. 7. When the pin 30 is moved past the dead center in the opposite direction, the jaws will be snapped into their closed position. For a full and complete disclosure of the jaw opening and closing mechanism reference is made to the Williams Patent 2,071,244.

15 In the machine in which the invention is preferably embodied, as above described, provision is made for moving the bag supporting member from a vertical position, as shown in Fig. 1, and in which position the bag section is preferably 20 filled, to a substantially horizontal position, as shown in Fig. 6, in which position the mouth and side edges of the bag section are sewn as the bag supporting member is continuously advanced. In the illustrated embodiment, the clamping jaw holder 16 is carried by an arm 36 pivotally mounted upon an endless carrier chain 38 provided with lugs 104 as illustrated in Figs. 1, 2 and 7. In order to rock the unit on its pivot 39 from a vertical to a horizontal position and return, the arm 36 is provided with a pin 40 arranged to be 30 received in a stationary track formed by the guides 42, 44 so that as the carrier is advanced, the position of the unit may be controlled. The stationary guides 42, 44 may be adjustably supported in a bracket 71 mounted on the platen 61 of the machine. The lower end of the arm 36 may be provided with an extension 46 in which an adjustable screw 48 is carried, the latter being arranged to rest against a stationary surface 50 35 in order to limit the movement of the unit at those portions of the machine where the stationary guides 42, 44 are omitted. The stationary surface 50 may also be extended to form a cam surface as shown in Fig. 6 for raising the unit 40 from its horizontal position into a position to be received between the guides 42, 44 for maintaining the units in their vertical position.

45 In the operation of the machine, as the bag supporting unit is carried along in its substantially horizontal position as shown in Fig. 6, provision is made for rotating the clamping jaw holder 16 on its own axis 54 in order that the open mouth and side edges may be successively presented to the various sewing heads, one of which is diagrammatically indicated at 52 in Fig. 6, as the bag section is advanced through the machine. As herein shown, the holder 16 is formed integrally with a stud 54 rotatably journaled in the arm 36 and rotation of the holder may be effected by the engagement of suitably formed projections 56 on the holder 16 with stationary pins 57 disposed in the path thereof. Each stationary pin 57, as shown in Fig. 6, may be supported in a bracket 59 mounted on the platen 61. Any suitable mechanism for retaining the holder in its rotated position may be provided, such as a locking stud 58, which is adapted to enter openings 63 provided in the holder. The rotatably mounted stud 54 is yieldingly mounted in the arm 36 whereby to permit the holder to be depressed against the resistance of a spring 60 in order to release the holder from its locking stud 58 prior to the rotating operation. The depression of the holder may be effected by a roller 69 also carried

in the bracket 59 and disposed in the path of the top of the stud 54, as shown. After passing a rotating station, the holder is again retracted by the spring 60 to seat the locking stud 58 into a succeeding opening 63 in the holder to again lock the unit in its rotated position.

In the illustrated embodiment of the invention, the bag sections are preferably filled while being moved along in their vertical position, as indicated in Fig. 1, and in the operation of the machine, as set forth in said Williams patents, the clamping jaws 10, 12 are arranged to close over the web 14 of bag making material after the filling tubes have entered therebetween. As herein shown, the filling mechanism may include a plurality of vertically movable tubes 62 arranged to move along with successive bag supporting units as they are being advanced, and after a charge of material has been deposited through the tube and into an individual bag section, the filling tube is then withdrawn. The web 14 may be severed between successive bag supporting units along the lines 64, see Fig. 2, to provide individual bag sections as the web is advanced, either prior to or after the filling operation.

In order to permit the clamping jaws 10, 12 to be closed upon the filling tube and to thereafter close upon the mouth of the bag after the filling operation and after the filling tube has been withdrawn, the clamping jaws, as herein shown, are provided with spring pressed upper flaps 65, 67, arranged to yield outwardly upon engagement with the filling tube, as illustrated in dotted lines in Fig. 1, and to subsequently close upon the mouth of the bag section, upon withdrawal of the filling tube as shown in Fig. 3. The flaps 65, 67 extend across the entire width of the jaws and as herein shown are hinged upon pins 70, 72 supported in the jaws 10, 12 respectively. The hinged flaps are urged inwardly into a position to grasp the mouth of the bag by coil springs 74, 76 as clearly shown in Fig. 2. Thus, when the bag supporting member is moved from its vertical to its horizontal position as above described, the tea is prevented from escaping through the mouth of the bag, and the mouth of the bag is held in a tightly closed condition for presentation to the sewing mechanism.

Referring now to Figs. 4 and 5, in order to positively hold the side edges of the bag in tightly closed position so as to prevent the escape of tea therethrough during the rotation of the bag as above described and also to reduce to a minimum the liability of slippage of the bag in its supporting member during operation thereon in the production of the bag, one of the clamping jaws, 12, is provided with a metal spring 80 riveted thereto and extending transversely of the jaw to present its outer edges 82, 84 in a position to engage the edges 86, 88 of the opposing jaw 10, as clearly shown in Fig. 5. The side edges of the clamping jaw 12 are grooved as shown at 90, 92 to provide clearance for the spring 80. Thus the side edges of the bag are yieldingly held in a tightly closed condition between the spring 80 and the edges 86, 88 of the jaw. In order to further assist in obtaining a firm grasp on the bag the side edges or bag engaging portions of the jaws 10, 12 are serrated or roughened as indicated in Fig. 4.

The mode of operation of the bag holding devices can best be described by reference to Fig. 7 in which the units are shown as embodied in a tea bagging machine of the construction shown in

Fig. 1 of the Williams Patent No. 2,351,382. As therein shown, a nozzle carrier 220 is provided above a portion of the carrier 38 for conveying the grippers 4 which carry the containers or bags to be filled. The grippers are adapted to be swung vertically and are also adapted to be rotated horizontally. The filling material, which may be tea, is carried in a hopper 8 concentric to the gripper carrier 38 at one end of the machine. The hopper is provided with measuring chambers which communicate one by one with a spout. The nozzles 62 are vertically movable on their carrier so that each will be lowered into an open substantially vertical gripper. Bag making fabric is drawn from a roll 9c thereof through the open grippers and shaped in the form of a V to receive the descending nozzles which serve as bag formers. The grippers are closed, one by one, on the bag material and around their nozzles. The latter then pass beneath the spout to receive tea from the hopper and subsequently are withdrawn from the grippers. The fabric strip 14 is cut transversely by a cloth knife, between adjacent closed grippers to form bag sections, each of which is thus carried by a gripper. The knife is so positioned that the lead end of the fabric strip is continuously being drawn by one or more of the closed grippers through one or more of the open grippers. The cloth knife is moved longitudinally with the fabric strip during the cutting thereof and is lowered out of the path of the grippers and nozzles during its return stroke. While the nozzles are being raised out of the bag sections any tea in the nozzles falls by gravity into the bag sections which are then carried by the grippers past a sewing or surging machine 52 for trimming and sewing the ends or mouths of the bag sections. The thread is cut and the grippers are lowered one by one, to a substantially horizontal position. One side of each bag section is positioned for being sewn and trimmed by either one of two spaced apart surging machines 52a, 52b adapted to form suitable stitching for attaching tags 17 to the bag sections. To space the tags from their bags, alternate grippers are swung to a position in which the bag sections carried thereby will not be engaged by the first 52a of the said two surging machines. The tags are fed to and sewn into the stitching at a maximum distance from their bags and the stitching is cut between the tags and the adjacent bag section. The grippers carrying the tagged bag sections are then swung upwardly to a position in which the tagged bags will not be engaged by the second 52b of the said two surging machines, and the grippers which were originally moved out of position for engagement by the first of the two surging machines are now lowered to position the untagged bag sections carried thereby for engagement by the second 52b of the two surging machines whereby tags are applied to the untagged bag sections. The stitching is cut between each tag and its adjacent bag section. The grippers carrying the first tagged bags are then lowered into alignment with the grippers carrying the second tagged bags and all the grippers are turned, one by one, 180° to bring the other, unsewn, side of each bag section into position for being trimmed and sewn by another sewing machine 52c. The three machines for sewing the mouths of the bags and for sewing one side and attaching the tags thereto are arranged along one side of the packaging apparatus and are driven by a sectional shaft so that each sewing

machine may be readily removed from the apparatus independently of the other sewing machines. The fourth sewing machine 52c is positioned on the opposite side of the apparatus. After the bags leave the fourth sewing machine the thread is cut, the grippers are released and turned 90°, the bags are engaged by a rotary clamping device 320, and the grippers are opened to permit the clamping device to remove the bags from their grippers and drop them onto a conveyor 280. All the grippers are then swung upwardly to a substantially vertical position to receive fresh bag making fabric.

From the above description it will be seen that the present bag supporting device is particularly adapted for use in a tea bagging machine of the character described wherein the bag making material comprises paper or like relatively firm and non-yielding material and that the construction of the supporting device is such as to render it capable of holding such paper bag securely closed so as to reduce to a minimum liability of slippage of the bag and to prevent escape of tea therefrom during its movement through the machine.

While the present device has been described as being particularly adapted for use in the production of paper containers, it will be understood that it is equally efficient for use in and may be used with advantage in a machine for producing cloth or other types of containers.

While the preferred embodiment of the invention has been herein illustrated and described, it will be understood that the invention may be embodied in other forms within the scope of the following claims.

Having thus described the invention, what is claimed is:

1. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of hollow clamping jaws pivotally carried on said frame and adapted to be closed about a bag having an open mouth portion, and a pair of pivotally mounted flaps carried by said clamping jaws and arranged to yieldingly engage said mouth portion to hold the latter in a securely closed condition when the clamping jaws are closed about the bag.

2. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of hollow clamping jaws pivotally carried on said frame and adapted to be closed about a bag having open side edges, and a yieldable member carried by one of said clamping jaws arranged to cooperate with the edge portions of the opposing clamping jaw to hold said side edges securely closed when said jaws are closed about the bag.

3. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of clamping jaws pivotally carried on said frame and adapted to

be closed upon a bag having an open mouth portion and open side edges, a pair of pivotally mounted flaps carried by said clamping jaws and arranged to yieldingly engage said mouth portion to hold the latter in a securely closed condition when said jaws are closed upon the bag, and a spring carried by one of said clamping jaws, said spring engaging the side edges of the opposing clamping jaw to hold said side edges securely closed when said jaws are closed upon the bag.

4. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of clamping jaws pivotally carried on said frame and adapted to be closed upon a bag having an open mouth portion and open side edges, a pair of pivotally mounted flaps carried by said clamping jaws and arranged to yieldingly engage said mouth portion to hold the latter in a securely closed condition when said jaws are closed upon the bag, and a spring carried by one of said clamping jaws, said spring engaging the side edges of the opposing clamping jaw to hold said side edges securely closed when said jaws are closed upon the bag, said pivotally mounted flaps and said spring cooperating to retain the bag in the supporting device.

5. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of clamping jaws pivotally carried on said frame and adapted to be closed upon a bag having an open mouth portion and open side edges, means carried by said clamping jaws arranged to hold said mouth portion in a securely closed condition, and a spring carried by one of said clamping jaws, said spring engaging the side edges of the opposing clamping jaw to hold said side edges securely closed and to prevent the bag slipping in the jaws.

6. In a tea bagging machine having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of clamping jaws pivotally carried on said frame and adapted to be closed upon a bag having an open mouth portion and open side edges, means carried by said clamping jaws arranged to hold said mouth portion in a securely closed condition, and a spring carried by one of said clamping jaws, said spring engaging the side edges of the opposing clamping jaw to hold said side edges securely closed and in substantially non-slipping condition, said clamping jaws being serrated or roughened at their bag engaging portions.

7. In a tea bagging machine of the type having a filling tube adapted to enter an open mouthed bag to perform the filling operation and to be withdrawn therefrom after the filling operation is completed and having an endless carrier chain provided with a plurality of carrier arms, each of said carrier arms being pivotally mounted on said chain and arranged to be swung in a vertical plane, bag supporting means com-

prising a frame adapted to be rotatably mounted on said arm and having a pair of hollow clamping jaws pivotally carried on said frame and arranged to be closed about the bag and the tube, and a pair of yieldably mounted flaps carried by said clamping jaws arranged to yield upon engagement with said tube, and to close upon the open mouth of the bag after the filling tube has been withdrawn.

8. In a tea bagging machine provided with a plurality of sealing devices arranged to seal the open side edges of a bag presented thereto while held in a supporting device and having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of hollow clamping jaws pivotally carried on said frame, and a yieldable member carried by one of the clamping jaws arranged to cooperate with the edge portions of the opposing clamping jaw to hold said side edges securely closed whereby to prevent the escape of tea therefrom during rotation of said jaws.

9. In a tea bagging machine of the type having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of hollow clamping jaws pivotally carried on said frame and adapted to be closed about a bag having an open mouth portion, said jaws also

being adapted to be moved from a vertical position in which the bag is adapted to be filled to a horizontal position in which the bag is adapted to be sealed, and a pair of pivotally mounted flaps carried by said clamping jaws arranged to close upon said mouth portion after the filling operation has been performed to hold the mouth in a securely closed condition whereby to prevent the escape of tea from the bag during movement from a vertical to a horizontal position.

10. In a tea bagging machine of the type having an endless carrier chain provided with a plurality of carrier arms, each of said carrier arms being pivotally mounted on said chain and arranged to be swung in a vertical plane, bag supporting means comprising a frame adapted to be rotatably mounted on said arm and having a pair of clamping jaws pivotally carried on said frame and arranged to be closed upon a bag having an open mouth portion and open side edges, said clamping jaws being adapted to be moved from a vertical position in which the bag is adapted to be filled to a horizontal position in which the bag is adapted to be sealed, said clamping jaws also being adapted to be rotated to dispose different edges of the bag in sealing position, a pair of pivotally mounted flaps carried by said clamping jaws arranged to close upon said mouth portion after the filling operation, and a spring carried by one of said clamping jaws, said spring engaging the side edges of the opposing clamping jaw to hold said side edges securely closed, whereby to prevent escape of tea from the bag during said movement of the clamping jaws.

LEWIS B. EATON.
